METHOD OF FLYING TOY AIRPLANE AND MEANS THEREFOR

Joseph E. Grant, Los Angeles, Calif.

Application February 4, 1950, Serial No. 142,475

12 Claims. (Cl. 46—81)

This invention relates to a novel method of imparting 15 free flight to miniature or toy airplanes and includes means whereby substantially continuous flight of a toy airplane may be attained.

Heretofore toy airplanes have been powered with various simple motors and rotation imparted to a propeller 20 or other device by means of tension motors, such as the well-known rubber band type, clockwork, springs, or even miniature internal combustion engines. More rudimentary types of toy airplanes, more properly termed gliders, depended entirely upon initial impetus given the airplane or 25 glider and as a result, the glide path was uncontrolled, erratic and of very short duration.

The present invention relates to a method whereby a small airplane can be caused to fly in a controlled manner without physical contact or mechanical connection with the operator or ground and without the use of a motor carried by the airplane. Flights of extreme duration and under the control of an operator can be attained. Level flight is the simplest form attained by the performance of the method herein disclosed, although turns, loops, and other aerial maneuvers can be performed by a more skilled operator.

Generally stated, the method of the present invention employs a simple, light-weight, miniature or toy airplane, preferably having certain distinguishing characteristics which will be described hereinafter. In imparting controlled but free flight to such airplane, the toy airplane is initially, temporarily supported in space, as by hand. A virtually vertical baffle is then moved beneath the airplane in a direction transverse to the plane of the baffle and in the desired direction of flight of the airplane, the support is released and the movement of the baffle is continued. Movement of the baffle plate gives rise to an up draft and the airplane rides along on such up draft out of contact with the baffle and totally unsupported by an extraneous object. The direction of flight may be controlled by varying the plane occupied by the moving baffle; height of the airplane above the upper edge of the baffle may be varied by either increasing or decreasing the rate at which the baffle is moved; the airplane may be caused to perform controlled turns or banks by pivoting the baffle (upon an axis perpendicular to its plane) during movement of the baffle along such axis; and other motions can be imparted to the airplane by controlling the movement and position of the baffle.

The airplane may be maintained in free flight for prolonged periods of time and the distance traveled by the airplane may vary with the walking ability of the operator manipulating the baffle. The method of operation herein disclosed may be utilized in devising and executing many predetermined maneuvers or in performing predetermined maneuvers, such as landing, precision bombing, or the like.

It is an object of the present invention, therefore, to disclose a novel method of controllably flying toy airplanes without physical contact between the airplane and the operator or the ground.

2

Another object of the invention is to disclose and provide a method of controllably flying toy airplanes which are free from motors, air screws, or other air-lift devices carried by the airplane.

5 Again, an object of the present invention is to disclose and provide simple, light-weight means whereby controllable flight may be imparted to toy airplanes.

A still further object of the invention is to disclose and provide conditions, proportions and arrangements whereby toy airplanes may be made and caused to fly without usual power means.

These and various other objects and advantages of the present invention will become apparent to those skilled in the art from the following description of the modes of operation and devices embraced by the present invention. In order to facilitate understanding, reference will be had to the appended drawings, in which:

Fig. 1 is a perspective view of a toy airplane in flight in accordance with the invention.

Fig. 2 is a somewhat enlarged side elevation of an airplane in flight above a moving baffle, only a portion of the baffle being illustrated.

Figs. 3, 4 and 5 are back, side and plan elevations, respectively, of a baffle plane which may be employed in carrying out the method.

Fig. 6 is a top rear view of a portion of a baffle plane provided with a different form of means for attaching the baffle to the hand of an operator.

Fig. 7 is a perspective front view of a modified form of baffle.

Figs. 8 and 9 are a plan elevation and a rear elevation, respectively, of a toy airplane adapted for use in performance of the method.

The mode of operation will be readily understood by referring to Figs. 1 and 2, wherein a small toy airplane, generally indicated at 10, is shown in flight. The airplane itself may comprise a fuselage stick 11 (made of light-weight material such as balsa wood, an organic plastic, or the like) provided with a wing 12 (preferably rectangular in plan or at least including a leading edge perpendicular to the plane of symmetry), such wing being made of some light-weight material bent or otherwise formed to produce a concave lower surface (best illustrated in Fig. 2). The wing may be made of veneer, sheet plastic (such as any of the cellulosic derivatives) or heavy rolled or coated paper. Stay pins or struts 17 may extend through openings near edge areas of the wing to maintain a desired wing curvature. The wing may be attached to the fuselage 11 by pins, adhesive, clips or a band. In most instances it is desirable that the ends of the wing 12 be provided with tips 13 at a dihedral to the wing proper.

It may be noted, however, that for best results it is desirable that the wing 12 be located toward the rear of the fuselage stick 11, the rear carrying both horizontal and vertical surface means such as the horizontal plane 14 and the upstanding, vertical surfaces 15. The distance between the trailing edge of the wing 12 and the leading edge of the horizontal surface 14 should be short, that is, between 2 in. and 5 in., and in most instances such distance is substantially equal to the chord length or width of the wing 12. Differently stated, it may be said that the leading edge of the wing 12 is preferably beyond the midpoint of the fuselage 11.

65 The baffle member illustrated in Fig. 1 consists of a virtually plane baffle 20 provided with means for attaching the baffle to the hand of an operator. In Fig. 1 the hand of the operator is shown extending beneath a strap 21 carried by the rear surface of the baffle 20, thereby permitting the hand of the operator to extend beneath the strap 21, the baffle becoming an extension of the palm of the operator. Such baffle 20 may be

made of any light-weight material, such as thin veneer or even paperboard reinforced with corrugations and laminated. The frontal surface area of such baffle may vary from about 0.5 sq. ft. to 10 or 12 sq. ft. but ordinarily a 2 to 5 sq. ft. baffle is adequate. The frontal area of the baffle is preferably three or more times as great as the plan form area of the wing of the airplane.

As indicated in Figs. 3, 4 and 5, the baffle plane 20 may be provided with a slightly cylindrico-concave face 22 and may be generally trapezoidal in form, the bottom edge 23 being substantially horizontal, whereas the side edges 24 and 25 incline downwardly and toward each other. The upper edge 26 may be slightly concave so as to leave rounded, upstanding corners indicated at 27 and 28. The slight curvature or convexity may be imparted to the baffle 20 by steaming, forming or in the event reinforced corrugated and laminated paper is employed, the corrugations preferably extend in a direction parallel to the bottom edge 23 and preformed, thin metallic bars or wires may be introduced into such corrugations, the curvature of the bars or wires imparting the desired curvature to the entire baffle.

In actual use, the toy airplane 10 is suspended in space temporarily by being held by a wing tip or by its fuselage with one hand, whereas the other hand of the operator is caused to move the baffle 20 from a position in the rear of the toy airplane into a position beneath the airplane. The baffle plane is moved with its frontal surface substantially vertical and in a direction transverse to the plane of the baffle and in the desired direction of flight of the airplane. As such baffle reaches a position beneath the airplane, the temporary support may be released, but the movement of the baffle plane is continued without interruption, the operator proceeding to walk and follow the airplane which is now in free but controlled flight.

By referring to Fig. 2, it will be seen that when the baffle plane 20 is moved in the direction of the arrow (from right to left) an up draft or upwardly rising current of air is generated, as indicated by the dashed arrows. The airplane 10 rides upon this up draft and it will be found that as long as the movement of the baffle 20 is continued the airplane will continue in free flight a distance of from 3 in. to 1 ft. above the upper edge of the baffle 20, the height depending somewhat upon the construction, gliding angle and weight of the airplane and the speed at which the baffle is moved by the operator. Normally the baffle should be advanced at a speed of between 150 ft. and 350 ft. per minute, although running speeds as high as 1000 or 1200 ft. per minute can be used. The operator may continue walking for prolonged periods of time with the airplane flying immediately above the baffle.

When it is desired to make a banking turn, the operator pivots the baffle 20 upon an axis transverse to the plane of the baffle. If, for example, an airplane is being maintained in flight as indicated in Fig. 1, a partial rotation of the baffle 20 in a clockwise direction (while its forward movement is continued) will cause the airplane 10 to perform a clockwise banking turn. Such turning maneuvers are facilitated by the concave upper edge 26 of the baffle, although the baffle may be provided with a straight upper edge if desired. Furthermore, although the preferred form of baffle plane includes downwardly and inwardly directed side margins 24 and 25 (Fig. 3) and such inclined sides facilitate pivoting of the baffle by eliminating undesired contact with the body of the operator during such pivotal movements, such margins 24 and 25 may be virtually perpendicular to either the bottom margin 23 or the top margin 26. It is to be understood that the drawings are simply illustrative of desirable constructions but the invention is not limited thereto.

Fig. 6 illustrates a modified form of construction which may be used wherein the means for attaching the baffle to the hand of an operator comprises a pair of paperboard members carried by the rear face of the baffle plane

20', said members acting to reinforce the baffle plane as well as furnish means for attachment to the hand. The rear surface of baffle plane 20' may carry one strip 31 stapled along a vertical edge as by means of staples 32, 5 such strip 31 being provided with a flap 33 having an opening 34 therein. The other strip is attached to the back of the baffle plane 20' along a spaced vertical portion 35 and includes a flap 36 having a lip portion 37. The flap 36 may be provided with a hand-hold opening 38.

10 During shipment, the strips 32 and 36 are flattened against the rear surface of the baffle plane 20'. When it is ready to place the baffle in condition for use, the two flaps 33 and 36 are bent upwardly so as to form a triangle, the lip 37 being then stapled onto the edge areas 15 of the flap 33 as by means of staples 39. The two hand-hold openings 34 and 38 are in opposition, permitting a hand to be inserted therethrough for the proper manipulation of the baffle plane. The triangular assembly or 20 or the like, materially stiffens the baffle plate and permits ready manipulation thereof. Other forms of construction (such as finger holes in the baffle) will readily occur from the descriptions given herein.

A modified form of baffle illustrated in Fig. 7 includes 25 a vertical groove formed in the face of the baffle. It has been found that vertical grooves can be formed in the face of the baffle and facilitate the maintenance and control of an airplane in flight. The simple form of baffle illustrated in Fig. 7 may be made from pressed board reinforced with horizontally extending corrugations between outer laminations of smooth paper. A central portion of this board, indicated at 20", is bent outwardly along lines 41 and 42 and inwardly along a vertical line 43 so as to form a triangular groove, the walls of such groove being 30 provided with opposing hand-hold openings 44. Relatively stiff wires 45, bent to the desired curvature, may then be inserted through some of the corrugations of the baffle, such wires being exposed while bridging the trough. The wires therefore maintain the triangular 35 trough in its proper form and at the same time impart a desired cylindrico-concave curvature to the front of the baffle. Additional vertical grooves may be formed on either side of the central groove. The construction illustrated in Fig. 7 is advantageous in that the entire device 40 can be readily flattened for shipment and is very easily assembled. In some instances it is desirable to position an auxiliary tape-like baffle across and in spaced relation to the front of the main baffle, said auxiliary baffle (shown in dash lines at 46) facilitating the production and 45 control of an up draft and tending to maintain the front surface of the main baffle in a desired curvature.

It is to be remembered that whenever reference is made 50 to continuously advancing the baffle in a direction virtually transverse to the plane of the baffle mathematical accuracy is not indicated. The vertical baffle may be slightly inclined to the true vertical, and particularly when making banking turns, the plane of the baffle may vary somewhat from the direction of flight or the predetermined pathway which is being traversed.

60 The device herein described may be employed in the performance of the method and numerous variations and amplifications of the method will be made available to those proficient in the performance of the method. For example, a toy airplane may be caused to perform a 65 loop by first causing the airplane to fly at a substantially uniform rate and then, by rapidly accelerating the motion of the baffle plate, the thus generated, increased up draft will cause the airplane to perform a loop. An operator of agility can rapidly move the baffle plane into proximity 70 with the airplane at the completion of its loop and again regain control of such airplane, causing the latter to either climb to its original altitude or continue flying at a lower elevation. The plane may be caused to perform the equivalent of an Immelman turn by rapidly accelerating 75 the forward movement of the baffle plane while one

of the upper corners of the baffle is at a higher elevation than the other.

Proper balance and gliding angle may be imparted to the toy airplane by moving a small weight, such as the weight 16, along the fuselage 11. When properly balanced, the airplane will glide for an appreciable distance at a uniform angle of descent. As a result, a skilled operator can fly the model airplane for an appreciable period of time and then cause it to make a landing at a predetermined spot or within a prescribed circle. When in flight, the gliding angle can be increased by either tilting the baffle or reducing the speed of movement of the baffle with respect to the airplane so as to direct the up draft against the rear of the plane (tail assembly), while level or upward flight is obtained by permitting the plane of the baffle to be directed toward the frontal or central portion of the wing. By moving the baffle along an upwardly inclined path, the airplane will gain altitude; by moving the baffle along a downwardly inclined path the airplane will lose altitude.

It is to be understood that various changes and modifications may be made in the construction and assembly of the devices referred to hereinabove and all changes and modifications coming within the scope of the appended claims are embraced thereby.

I claim:

1. A method of controllably flying toy airplanes which comprises: temporarily supporting an airplane in space; moving a virtually vertical baffle plane beneath the airplane in a direction virtually transverse to the plane of the baffle and in the desired direction of flight of the airplane to produce an upwardly directed stream of air; then releasing the support and continuing the movement of the baffle plane at a rate sufficient to maintain the airplane in free flight upon the upwardly directed stream of air.

2. A method of controllably flying a toy airplane, which comprises: continuously advancing a virtually vertical baffle plane in a direction virtually transverse to the plane of the baffle along a pathway to produce an upwardly directed stream of air; and maintaining a toy airplane in free flight above said baffle by advancing the baffle at a speed of between 150 ft. and 1000 ft. per minute.

3. In a method of the character stated in claim 2, the step of placing the toy airplane into a controlled banking turn during flight which comprises partially rotating the baffle plane about an axis virtually perpendicular to the plane of the baffle while advancing the baffle along the pathway.

4. In a method of the character stated in claim 2, the step of controlling the vertical angle of flight of the airplane by varying the position of the plane of the baffle with respect to the wing and tail surfaces of the airplane.

5. In a method of the character stated in claim 2 wherein the baffle is moved along a pathway inclined to the horizontal.

6. A device for maintaining and controlling a toy airplane in free flight comprising: a baffle member of generally trapezoidal form, the upper marginal edge of the baffle member being concave and the front surface being concave, said member being of lightweight sheet material and being provided with means for receiving the hand of an operator while said hand is substantially parallel to the top and the bottom of said member for attaching the baffle member to the hand of the operator.

7. A baffle of the character stated in claim 6 wherein the front surface area of the baffle is between about 2 and 5 square feet.

8. A baffle of the character stated in claim 6 wherein the baffle is provided with a virtually cylindrico-concave front surface.

9. A baffle of the character stated in claim 6, wherein the attaching means are carried by the rear surface of the baffle member.

10. A baffle of the character stated in claim 6, wherein the attaching means comprise a hollow, triangular, vertically extending reinforcing assembly provided with aligned hand holds, said means being carried by and extending rearwardly from the rear surface of the baffle member.

11. A device for maintaining and controlling a toy airplane in free flight comprising: a thin baffle member of sheet material, said member being generally trapezoidal in form and including downwardly converging side margins, a substantially straight bottom margin and a concave upper margin, the member being bent to present a cylindrico-concave front face having an area of between 0.5 and 12 square feet; and hand-holding means centrally disposed at the rear of the baffle member and provided with an elongated hand-receiving aperture extending vertically.

12. A device of the character stated in claim 6, wherein the baffle is made of laminated, corrugated board, with a vertically extending groove formed in the face of the baffle.
